D 18,795

Design No. 18,795, dated December 11, 1888.

UNITED STATES PATENT OFFICE.

ALEXANDER T. HENDERSON, OF DETROIT, MICHIGAN.

DESIGN FOR A GAS-STOVE.

SPECIFICATION forming part of Design No. 18,795, dated December 11, 1888.

Application filed July 31, 1888. Serial No. 281,565. Term of patent 7 years.

To all whom it may concern:

Be it known that I, ALEXANDER T. HENDERSON, of Detroit, in the county of Wayne and State of Michigan, have invented a new and useful Design for a Gas-Stove, of which 5 the following is a specification.

The object of this design is to provide a novel gas-stove; and it consists in the features hereinafter described and claimed, and shown 10 in the accompanying photograph, which represents a perspective view of a gas-stove embodying my design.

The stove comprises a front divided into an upper and a lower section, A B, separated by 15 a horizontal band-like space or panel, E. The upper section, A, has a door, C, and the lower section, B, has a door, D, each ornamented by a surrounding scroll-work resembling the conventional figure of palm-leaves. The center of the door C has a panel, M, and the center of the door D has a panel, F.

The letter K indicates the leg-base, and L the legs. From the side of the lower section 20 of the stove extends a substantially triangular-shaped bracket, G, carrying a top plate, I, the latter being about midway between the top and bottom of the stove. The doors C D are bulged out or rounded instead of flat. The upper section, A, has a top plate, H.

30 What I claim, and desire to secure by Letters Patent, is—

1. In a design for a gas-stove, the front

plate divided into the upper and lower sections, A B, provided, respectively, with the doors C D, having center panels, M F, and surrounding palm-leaf ornamentation, substantially as shown and described. 35

2. In a design for a gas-stove, the body comprising the front plate divided into the upper and lower rectangular sections, A B, having 40 the shape and ornamentation shown, and provided, respectively, with the upper and lower outwardly-bulged doors, C D, the upper door having the central panel, M, and the lower door the central panel, F, substantially as 45 shown and described.

3. In a design for a gas-stove having the shape and ornamentation shown, the triangular-shaped bracket G and the top I above the bracket and at a point about midway between the top and bottom of the stove, substantially as shown and described. 50

4. The design for a gas-stove having the shape and ornamentation shown, the doors C D, containing the panels M F, the horizontal 55 band-like panel E, the triangular-shaped bracket G, and the top I above the bracket and about midway between the top and bottom of the stove, substantially as shown and described.

ALEXANDER T. HENDERSON.
